UNITED STATES PATENT OFFICE.

FRANCIS WALTER ALTPETER, OF CHICAGO, ILLINOIS.

DRAFTSMAN'S RULE.

SPECIFICATION forming part of Letters Patent No. 530,741, dated December 11, 1894.

Application filed April 5, 1894. Serial No. 506,379. (No model.)

To all whom it may concern:

Be it known that I, FRANCIS WALTER ALTPETER, a citizen of the United States, residing at Chicago, in the county of Cook and State of Illinois, have invented certain new and useful Improvements in Draftsmen's Rules; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to adjustable rules for draftsmen's use, its object being to improve the joint in rules adapted to be used as straight edges or as ninety degree angles or as section liners or to be folded to one half 20 their total length.

The invention consists of the use of an extensible arm pivotally attached to both members of the rule, its pivot pin upon one member being longitudinally movable; and of a 25 spring for contracting the arm.

In the drawings I show in Figure 1, a plan view of my improved rule extended as a straight edge, on a scale of one-half inch to the inch; Fig. 2, a similar view, the joint 30 being broken to bring one member into perpendicular relation as to the other. Figs. 3 to 7, inclusive, are details of the joint. Fig. 8, is a plan view of the rule folded; and Fig. 9, is a bottom plan of adjacent ends of the 35 two members, in full size.

The two members, A, B, of the rule are shown as of equal length and width and one of its edges beveled and provided with a scale of linear inches, its other edge being vertical. 40 Member, A, has a longitudinal channel along its upper surface, the channel having an inwardly projecting flange, or lip, on each side. A screw threaded stud, E, having an elongated T-head, e, is carried in this channel, 45 being adapted to slide freely therein. An apertured block, D, is pivotally attached to the member, B, by the pin, d, near one of its ends. An arm, C apertured at one end to fit loosely upon the stud, E, and having its other 50 end fitted loosely within the aperture of the

block, D, unites the two members, A, B. The arm C, is secured within the block, D, by means of the pin, c, fixed transversely across the aperture of the block and extending through a longitudinal slot in the arm, a spiral 55 spring, c', reacting between the pin, c, and the outer end of the arm so as to normally draw the arm, C, within the aperture of the block, D, until the end of its slot strikes the pin, c. A nut, F, fits upon the stud, E, and when 60 turned down draws the arm, C, firmly against the surface of the member, A, and the block, e, against the flanges of its channel thereby preventing the stud from being moved within the channel. A jam nut, f, may be employed 65 to prevent the accidental turning of the nut, F. The inner end of the member, B, is concave as shown at b, and the vertical edge of the member, A, has a concave recess, a, near its inner end.

When the rule is straight, as shown in Fig. 1, a pin, k, set in the inner end of the member, A, near its beveled edge, engages a socket correspondingly located in the adjacent end of the member, B. The rule is thereby prevented from having its joint broken without the application of longitudinal strain to the two members in opposite directions for the purpose of separating them by compressing the spring, c'. When the member, B, is released from engagement with the pin, k, it is readily turned on the stud E, and the recess, b, facilitates this movement. When in the position shown in Fig. 2, the member, B, being perpendicular to the member, A, the former will readily slide upon the latter if the nut, E, is loose, and the tool is now a convenient instrument for drawing parallels, as in section lining.

The two members are folded together in the 90 position shown in Fig. 3. By carrying the member, B, when perpendicular to the member, A, to the inner end of the latter when its vertical edge is over the recess, a, the member, B, turns upon its pivot pin, d. A stud pin, k, 95 set in the vertical edge of the member, A, engages a socket indicated at k', correspondingly located in the member, B, and prevents the one sliding upon the other.

The pin, d, is formed with a recess in its 100

outer end so that its edges may be flared out by the use of a suitable tool, thereby locking it within its aperture. The arm, C, is formed with an off-set to bring its outer end against 5 the surface of the member A.

Usually the nut, F, will not be turned down so as to bind upon the arm, C, but will merely be brought into frictional contact with it, and locked in that position by the jam nut, f. The 10 tension of the spring, c', will be sufficient to prevent the member, B, from being readily displaced when in its angular position.

I claim as my invention—

1. The combination in a draftsman's rule, 15 of the two members, A, B, the member A having a longitudinal channel with contracted opening, a T-headed stud, E, projecting outwardly and adapted to slide in the channel, and a spring retracted extensible arm for uniting 20 the two members and being pivoted to the member, B, and apertured to receive the stud, E, substantially as described and for the purpose specified.

2. The combination, in a draftsman's rule, 25 of a member, A, having a longitudinal channel with contracted opening, a block adapted to slide within the channel, a stud E, set in the block and projecting outwardly through the channel opening, a member, B, adapted 30 to be joined to the member, A, end to end, or to have its end abut against the edge of member A, and slide thereon, and having its abutting end recessed to facilitate change of angular position, a spring retracted arm for uniting 35 the two members and being pivoted to the member, B, and recessed to receive the stud, E, substantially as described and for the purpose specified.

3. The combination, in a draftsman's rule, of two members, A, B, adapted to co-operate 40 end to end, or the one perpendicular to the other, of a spring retracted arm for uniting the two members, said arm being pivoted to one member by a fixed pin and to the other by means of a pin adapted to move longitudinally upon said member, substantially as described and for the purpose specified. 45

4. In an adjustable draftsman's rule, the combination with the member A, having a square end and a concave recess in one of its 50 edges near such end, of a member, B, a spring retracted arm for uniting the two members and being pivoted to the member, B, at a fixed point and to the member, A, by a movable pin, whereby the end of the member, B, may 55 be held in contact with the recessed edge of the member, A, said recess allowing the member, B, to be turned to bring its edge against the edge of the member, A, substantially as described and for the purpose specified. 60

5. The combination, in a draftsman's rule, of two members, A, B, adapted to co-operate end to end or the one perpendicular to the other, of a spring retracted arm, C, for uniting the two members, said arm being pivoted 65 to the member A, a socketed block attached to the member B, the arm C being adapted to slide within such socket, substantially as described.

In testimony whereof I affix my signature in 70 presence of two witnesses.

F. WALTER ALTPETER.
